LOAD SUSPENSION APPARATUS AND
RELATED METHODS

Salvatore Vincent Giardina, Brooklyn, N.Y., assignor of
one-half to Pasquale Fichera, Brooklyn, N.Y.
Filed Mar. 8, 1962, Ser. No. 178,439
9 Claims. (Cl. 52—39)

This invention relates to load suspension apparatus and to associated methods and is more particularly concerned with improved techniques for suspending large loads from frangible overhead structures of masonry and the like.

A principal object of the invention is to provide improved techniques whereby the load supporting characteristics of masonry structures and the like are vastly improved.

A further object of the invention is to insure against failure in load suspending mechanisms by the use of simple and economical improvements.

Still another object of the invention is to provide an improved technique which does not require the passing of a suspending structure completely through the associated supporting structure so that orientation of suspension location is greatly facilitated.

Yet another object of the invention is to make optimum use of related suspension apparatus components by advantageously dissipating displacement forces therein in shear as will become hereinafter apparent.

Still a further object of the invention is to employ vertical suspension components in such a manner that they provide horizontal reaction components for improving associated safety factors.

Another object of the invention is to make hanger structures slip and failure proof.

A further object of the invention is to avoid the need for drilling through floors and the like for the purpose of mounting hangers therefrom, thus avoiding the need for refinishing and/or repairing such floors.

A still further object of the invention is to achieve with the use of pins an assurance against failure which is not normally achieved by the use of steel concrete inserts which the pins replace.

Yet another object of the invention is to provide means for effectively putting concrete structures and the like in compression to improve the load supporting characteristics thereof.

Briefly, the invention contemplates a technique whereby a hanger bracket or the like is fastened to an overhead structure by such means that the tendency of the bracket to be pulled away from the overhead structure by a load on said bracket is resolved into vertical and horizontal forces, the latter of which is applied to a vertical member or the like in shear so that an optimum resistance to displacement of the bracket is provided.

In accordance with one object of the invention, the aforenoted horizontal force is transmitted to the vertical member through the intermediary of the bracket itself. However, according to a still further object of the invention, the transmission of the horizontal force may be effected through a member which is physically separate from the bracket.

According to still a further feature of the invention, there may be provided a supplemental member for transmitting at least a part of this horizontal force and this supplemental member may, according to a particular embodiment of the invention, be employed to further hold a fastening member in place, as will become hereinafter apparent.

The invention contemplates preferably the use of one or more inclined pins or like fastening members whereby the resolving of load forces into its horizontal and its vertical components may be readily accomplished and,

2

according to one embodiment of the invention, there may be associated with such inclined pins vertically disposed bolts or the like accommodated in expansion shields provided with bores in the associated overhead structure.

According to still another object of the invention, a special means can be provided for putting masonry structure into compression whereby the strength of the structure and resistance to fracture or deterioration is greatly improved.

In accordance with still another feature of the invention, a disc-like structure is provided on a load bearing member in such a manner as to resist the withdrawal of inclined pins out of the associated bores provided in the related overhead structure.

Yet another feature of the invention relates to the particular arrangement of load bearing members relative to the associated inclined and vertical fastening members, whereby failure due to large loads may be substantially completely avoided.

Other objects and features, as well as advantages, of the present invention will become apparent from the following detailed description of some preferred embodiments which are illustrated in the accompanying drawing in which:

FIGURE 1 illustrates a first embodiment of the invention wherein are employed inclined and vertical fastening members and a means for resisting removal of at least one of these members from the associated bore;

FIGURE 2 illustrates, in side view, a further embodiment of the invention wherein one of the fastening members is fixed to the associated bracket;

FIGURE 3 illustrates, in side view, still another embodiment of the invention wherein the element for transmitting at least a part of the aforenoted horizontal force is separable from the associated bracket;

FIGURE 4 is a side view of still another embodiment of the invention wherein is provided an element for placing the associated concrete structure under compression; and

FIGURE 5 is illustrative of still another embodiment of the invention wherein is provided a special element for avoiding withdrawal of one of the associated fastening members.

The embodiment of the invention illustrated in FIGURE 1 comprises, generally a bracket 10, a load suspension member 12 and fastening elements 14 and 16. An auxiliary element 18 is also provided for purposes which will become hereinafter apparent.

The purpose of the structure illustrated in FIG. 1 is to provide means for suspending a load (not shown) from an overhead masonry structure 20 which may be constituted by concrete or the like.

At the outset of the description of the embodiment of the invention illustrated in FIG. 1, it is to be noted that the fastening elements of this embodiment do not pass completely through the overhead structure 20, although this is a possibility, if necessary. However, the fact that the fastening elements do not pass completely through overhead structure 20 clearly facilitates locating the hanger arrangement in that it is unnecessary to drill through structure 20 from above whereby the need for repairing the upper surface of structure 20, which may constitute a floor, is avoided.

More particularly, element 10 is a knee bracket fabricated of steel, or a like metal having suitable strength, element 10 comprising a horizontal arm 22 and a vertical arm 24, said arms being perpendicularly related and defining an angle of 90° therebetween. This arrangement is preferable. However, other angles may be substituted in a situation where the structure 20 presents an inclined lower surface, it being generally preferred that the arm 24 be arranged in vertical disposition. It will be noted

that horizontal arm 22 rests in face-to-face abutting relationship against the lower surface of the overhead structure 20.

Element 12 is a load suspension member. It is comprised of a vertical limb 26 provided with a loop or ring member 28 wherefrom the load itself is suspended. Element 12 is further provided with a section 30 wherethrough extends a threaded bolt 32 having a head 34 and provided with a nut 36 and a washer 38 by means of which a firm connection is provided between elements 10 and 12.

Extending through arm 22 of element 10 are two spaced holes 40 and 42. Hole 40 has generally a vertical disposition, for a purpose which will become hereinafter apparent, whereas hole 42 is preferably although not necessarily inclined, also for a purpose which will become hereinafter apparent.

In correspondence with holes 40 and 42 are provided bores 44 and 46 drilled, or otherwise formed, in overhead structure 20. Bore 44 is preferably vertically disposed and concentric with hole 40. Bore 46 is inclined by an angle A relative to the vertical, angle A being preferably in the order of 30°. Bore 46 is preferably concentric with hole 42 in arm 22.

Also provided on the arm 22 is an inclined sleeve 48 concentric or coaxial with hole 42 and bore 46. Sleeve 48 is provided with an internal bore through which passes fastening element 14 and the sleeve 48 is preferably affixed to horizontal arm 22 by welding or the like.

In bore 44 is provided an expansion shield 50 of conventional structure. The expansion shield 50 is vertically disposed and in known manner is expandable within the bore 44 for being firmly engaged with the same.

Fastening element 14 is preferably, in this embodiment of the invention, a pin including a dome-shaped head 52. According to the method involved in this embodiment of the invention, the pin 14 is driven with a mallet or hammer through sleeve 48 into bore 46 within which the pin is frictionally engaged. The pin 14 is driven into bore 46 until head 52 moves into abutting relationship with the end of sleeve 48.

Into the expansion shield 50, in accordance with the method of this embodiment of the invention, is inserted a bolt 54 having a head 56 which sandwiches arm 22 against overhead structure 20. However, between arm 22 and head 56 is accommodated a flat section 58 of the auxiliary member 18 which is constituted by a spring clip of steel or other such suitable material.

Auxiliary member 18 further comprises an arcuate section or extension 60 connected to the horizontal section 58 and positioned for engagement with the dome-shaped head of pin 14.

In the aforesaid embodiment of the invention, it will be seen that when a load is connected to section 30 of load suspension member 12, the tendency for bracket 10 to be pulled away from overhead structure 20 will be greatly resisted by the pin 14 whose disposition is purposefully planned to be closer to the vertical arm 24 than is the disposition of bolt 54. Thus, pin 14 is strategically located to avoid possible pivoting movement of bracket 10 about a pivot point which might be constituted in the arm 22 in the vicinity of said bolt 54.

In addition, it will be noted that any tendency of pin 14 to move axially out of bore 44 will be resolved into a vertical force downwardly directed and a horizontal force directed to the left, this resolution being effected through sleeve 48 and through arm 22. The horizontal force which might take place towards the left, is transmitted to bolt 54 in shear, this being the type of stress which the bolt 54 is most capable of resisting. Thus, a vertical fastening member, which normally would not have any significant effect in supporting the load, is efficiently employed to resist detaching of the bracket 10 from the overhead structure.

In addition to the significant advantages noted above,

the auxiliary element 18 provides still further advantages. On the one hand, element 18 resists axial displacement of the pin or fastening element 14, whereas still further this element converts axial displacement tendencies of pin 14 into horizontal vectors applied at right angles or in shear to the bolt 54 which element is most capable of resisting stresses applied in this manner.

The embodiment of the invention illustrated in FIG. 2 is a variation of that illustrated in FIG. 1. This embodiment contemplates the use of a load suspension member 70 connected by a nut and bolt arrangement 72 to a knee bracket 74, the knee bracket 74 being mounted on an overhead structure 76 by means of an inclined pin 78 and a vertically disposed bolt 80 accommodated in an expansion shield 82 housed in a corresponding vertical bore.

In this embodiment of the invention, there is provided an inclined sleeve 84 which, however, is provided with an internal thread 86 with which is threadably engaged threaded portion 88 at the lowermost end of said pin 78.

Pin 78 includes a threaded portion 90 extending downwardly out of the sleeve 84, a nut 92 being threadably engaged on said portion 90.

According to the technique contemplated in accordance with this embodiment of the invention, pin 78 is threaded through sleeve 84 and nut 92 engaged threadably with end portion 90. Thereafter, the nut 92 is riveted or otherwise affixed by a pin or the like to the end portion 90.

In further accordance with this embodiment of the invention, the pin 78 is affixed to the bracket 74 and is then hammered home in the associated inclined bore until the bracket 74 moves into close fitting relationship with overhead structure 76. Thereafter bolt 80 is inserted into expansion shield 82 whereupon the load suspension member 70 may be affixed to bracket 74 by nut and bolt arrangement 72.

As in the originally described embodiment of the invention, any tendency of pin 78 to move axially out of the associated bore is converted by sleeve 84 and bracket 74 into vertical and horizontal components, the latter of which is applied at right angles to bolt 80 in shear, the bolt 80 presenting a maximum resistance to this force and thus to a detaching of the bracket 74 from overhead structure 76.

Again it is to be noted that the inclined pin 78 is preferably arranged closer to the vertical arm of the bracket 74 than is the bolt 80 so as to provide a maximum effective resistance to the load suspension member 70.

Although the use of specific pin and bolt and expansion shield members has been indicated relative to FIGS. 1 and 2, it should be noted that while these elements are preferable other modifications are possible, the pins and bolts representing simply specific cases of fastening elements for which substitutes can be made within the scope of the invention.

The embodiment of the invention of FIG. 3 illustrates still a further variation of the invention wherein a detachable element is provided for purposes of transmitting horizontal forces as aforesaid and for resisting axial movement of inclined pins.

More particularly, an overhead structure 100 in FIG. 3 is provided with inclined bores 102 and 104 within which are respectively accommodated and frictionally engaged pins 106 and 108 having respectively heads 110 and 112. Preferably, bores 102 and 104 and pins 106 and 108 are inclined at about 45° to the horizontal.

In addition, there is provided a plate 114 in face-to-face relationship with the lower surface of overhead structure 100, said plate being fabricated of steel or other such material having suitable strength.

On the lower surface of plate 114 are provided inclined sleeves 116 and 118, plate 114 being provided with inclined holes 120 and 122 concentric and coaxial

with bores 102 and 104 respectively and sleeves 116 and 118 respectively.

Inasmuch as heads 110 and 112 are generally arranged at right angles to the associated pins, the free surfaces or extremities thereof, which are flat, also define angles of 45°. The purpose of these angles will become hereinafter apparent.

Threadably and detachably affixed to plate 114 and centered between the aforesaid sleeves and pins is a threaded bolt 124 on which is loosely accommodated a disc 126 having a central bore 128, the diameter of which exceeds the outer diameter of threaded bolt 124. The disc 126 is generally in the form of a truncated cone having a base angle of 45° such that its inclined peripheral surface 130 is adapted to engage flatly against the free extremities of heads 110 and 112 of pins 106 and 108.

A nut 132 is threadably engaged on the lower extremity of bolt 124 and urges disc 126 outwardly against heads 110 and 112.

According to this embodiment of the invention, the disc 126 resists axial displacement of pins 106 and 108 downwardly out of bores 102 and 104, each pin acting in opposition to displacement of the other of said pins. Moreover, bolt 124 constitutes a vertical element to which the horizontal vectors of the downward movement of pins 106 and 108 are applied perpendicularly or in shear.

In the embodiment of FIG. 3, a load supporting member (not shown) can be threadably affixed to the lower extremity of bolt 124.

The aforesaid device avoids the use of expanded metal shields and an applied load is equally distributed by inclined pins 106, 108 into the associated masonry.

In this and in the aforesaid embodiments of the invention, the required bores in the masonry can be provided by using the inclined sleeves as drill guides. Alternatively, a drilled fixture can be held in position with an expansion shield and bolt.

A further embodiment of the invention is illustrated in FIG. 4 wherein is included an element adapted for placing the associated masonry under compression.

More particularly, in FIG. 4, there are provided pins 140 and 142 driven into associated bores and arranged at approximately 22½° from the vertical. A plate 144 is provided having thereon inclined sleeves 146 and 148, there also being provided a detachable bolt 150 in vertical disposition and depending downwardly from plate 144.

In this embodiment of the invention a disc 152 having inclined surfaces 154 and 156 is urged upwardly against the ends of pins 140 and 142 by means of a nut 158.

In addition, there is provided a disc 160 urged downwardly by a nut 162 against the inner surfaces of pins 140 and 142 so that these pins tend to pivot with the sleeves 146 and 148 acting as fulcra. It will be understood that sleeves 146 and 148 can be omitted in which event plate 144 acts as the fulcra. If the holes in the plate are one thirty-second of an inch larger than the pins 140 and 142, sufficient compression results.

Due to this pivoting tendency of pins 140 and 142, the inner extremities of said pins accommodated within the masonry structure act to compress the masonry structure thereby greatly increasing the effectiveness thereof.

More particularly, it will be noted that the disc 152 is in the shape of an inverted truncated cone, the peripheral surface of which inclines at an angle corresponding to the side surfaces of the pins 140 and 142. Surfaces 154 and 156 of disc 152 are arranged at an angle of about 22½° to the horizontal in order to correspond with the free extremities of the inclined pins.

According to the embodiment of the invention illustrated in FIG. 5, there is contemplated a still further variation of the method and apparatus of the invention.

More particularly, the embodiment of the invention illustrated in FIG. 5 comprises a first knee bracket 170 fastened to an overhead masonry structure 172 and including arms 174 and 176 respectively disposed in horizontal and vertical planes and rigidly connected at a right angle.

As in prior embodiments of the invention, there is provided an inclined sleeve 178 affixed to the horizontal arm 174 by welding or the like and concentric with a bore 180 formed in the overhead structure 172.

A pin 182 is provided including a head 184 by means of which the said pin is driven into bore 180 for frictional engagement therein.

A second fastening member is provided in the form of a bolt 186 which is threadably accommodated in an expansion shield 188 accommodated within a vertical bore in overhead structure 172. The head in bore 186 sandwiches arm 174 against said overhead structure and cooperatively with pin 182 and the head 184 thereof holds the horizontal arm 174 firmly against the overhead structure.

In accordance with this last embodiment of the invention, there is further provided an angle support means 190 including a vertical arm 192 and a horizontal arm 194. Vertical arm 192 is in face-to-face relationship with said vertical arm 176 and the two are connected by a nut and bolt locking arrangement 196.

The horizontal arm 194 is located beneath horizontal arm 174 and is preferably in horizontal relationship with respect thereto. An internally threaded sleeve 198 is mounted in vertical disposition directly beneath the head 184 of pin 182 and accommodates therein a vertical, externally threaded rod 200. This rod is threadably engaged within the sleeve 198 and adjusted so as to be in endwise engagement with pin 182 and, more particularly, the head 184 thereon. Rod 200 is adapted for supporting a load which, in accordance with the method of the invention, is suspended by conventional means from said rod.

According to the method of the invention relating to this embodiment, vertical and inclined bores are formed in the overhead structure 172 in correspondence with the holes provided in the horizontal arm 174 of bracket 170. Pin 182 is selected so as to be slightly larger in transverse dimensions than bore 180 and is driven home in the latter to be engaged frictionally within the same. Bolt 186 is threadably engaged with expansion shield 188 in the associated vertical bore and then angle 190 is connected to bracket 170. Thereupon the sleeve 198 is set to accommodate rod 200 which is threaded into the same and into endwise engagement with head 184 of pin 182, the rod 200 thereby resisting oblique movement of pin 182 out of bore 180.

In this embodiment of the invention as in the prior embodiments, the tendency of pin 182 to move downwardly in response to the application of a load to rod 200 is resolved into horizontal and vertical vectors, the horizontal vector of which is transmitted via horizontal arm 174 at right angles against bolt 186 which therefore receives the same in shear.

There have now been described five embodiments of the invention in association with each of which is contemplated an apparatus and a method. In each of the embodiments of the invention, there is contemplated the resolving of the movement of a pin or other such fastening member out of an inclined bore in an overhead structure into vertical and horizontal vector forces, the latter of which is applied at right angles to a further fastening member or the like so that the latter receives the horizontal force in shear. This technique adds greatly to the use of inclined fastening members and furthermore makes a use of vertically disposed fastening members which has not heretofore been contemplated.

According to one aspect of the invention, the transmission of the horizontal vector force is effected through

the bracket itself to a vertically disposed fastening member, whereas in accordance with a further aspect of the invention the horizontal vector force is transmitted externally of the associated bracket. In some cases, as has been illustrated, both the bracket and a member external thereto may be employed to transmit the associated vector force.

In addition, a further aspect of the invention relates to engaging of elongated fastening members such as pins, bolts and so forth in endwise manner in order to resist axial movement of such fastening members from the associated overhead structure.

While reference has been made above to the provision of bores accommodating fastening members, it will be readily appreciated that the invention contemplates methods in which a fastening member is driven home into a masonry structure or the like without the prior provision of bores in the latter. This, of course, depends upon whether or not the structure to which connection is to be made will tolerate such an operation.

In accordance with still a further aspect of the invention, there is contemplated the control of strain patterns within supporting structures such as by placing the same controllably under compressive stresses.

There will now be obvious to those skilled in the art many modifications and variations of the structures and methods set forth above. These modifications and variations will not, however, depart from the scope of the invention if defined by the following claims.

What is claimed is:

1. For use with an overhead structure provided with two oppositely inclined bores, an anchor hanger comprising a plate provided with oppositely inclined holes concentric with said bores, pins extending through said holes and frictionally engaged in said bores, said pins including free extremities, a member depending from said plate between said pins, a disc freely displaceable on said member and having a periphery for engaging against and between said extremities and means adjustable on said member for forcing said disc against said extremities.

2. In combination with an overhead structure provided with two oppositely inclined bores, a hanger comprising a plate provided with oppositely inclined holes concentric with said bores, pins extending through said holes and frictionally engaged in said bores, said pins including flat free extremities inclined at a predetermined angle to the horizontal, a vertical member detachably depending from said plate between said pins, a truncated conical disc freely displaceable on said member and having a base angle equal to said predetermined angle to provide an inclined periphery for engaging against and between the inclined extremities, and means for locking said disc against said extremities.

3. For use with an overhead masonry structure provided with two oppositely inclined bores arranged at about forty-five degrees to the horizontal, an anchor hanger comprising a horizontal plate in face-to-face relation with said overhead structure and provided with oppositely inclined holes concentric with said bores, downwardly depending inclined sleeves on said plate concentric with and encircling said holes, pins extending through said sleeves and holes and frictionally engaged in said bores, heads on said pins and abutting against said sleeves, said heads including flat free extremities inclined at about forty-five degrees to the horizontal, a vertical member depending from said plate midway between said heads, a truncated conical disc freely displaceable on said vertical member and having a base angle of about forty-five degrees to provide an inclined periphery for engaging against and between the inclined extremities of said heads, and means on said vertical member locking said disc against said extremities.

4. In combination with an overhead masonry structure provided with two oppositely inclined bores arranged at about forty-five degrees to the horizontal, an anchor

hanger comprising a horizontal plate in face-to-face relation with said overhead structure and provided with oppositely inclined holes concentric with said bores, downwardly depending inclined sleeves on said plate concentric with and encircling said holes, pins extending through said sleeves and holes and frictionally engaged in said bores, heads on said pins and abutting against said sleeves, said heads including flat free extremities inclined at about forty-five degrees to the horizontal, a vertical threaded bolt detachably depending from said plate midway between said heads, a truncated conical disc freely displaceable on said bolt and having a base angle of about forty-five degrees to provide an inclined periphery for engaging against and between the inclined extremities of said heads, and a nut on said bolt locking said disc against said extremities.

5. For use on an overhead structure, a hanger comprising means provided with spaced holes, fastening members extending through said holes and engaged at an angle in said structure, said members including inclined extremities, a guide on said means between said extremities, a retainer displaceable on said guide and engaging against and between the inclined extremities, means locking said retainer against said extremities, and means between the fastening members to urge the same apart.

6. In combination with an overhead structure provided with two oppositely inclined bores, apparatus comprising a member provided with spaced holes corresponding to said bores, sleeves on said member encircling said holes, fastening devices extending through said sleeves and holes and engaged in said bores, said devices including free extremities, a guide on said member between said devices, a retainer displaceable on said guide and having a periphery for engaging against and between said extremities, means for locking said retainer against said extremities, and means between the fastening devices to urge the same apart.

7. An anchor hanger comprising a plate provided with spaced holes, downwardly depending inclined sleeves on said plate encircling said holes, inclined pins extending through said sleeves and holes, said pins including free extremities, means depending from said plate between said pins, a disc displaceable on said pins and having a periphery for engaging against and between the said extremities, and means for locking said disc against said extremities, and means between the pins, outwardly of said plate, to urge said pins apart.

8. In combination with an overhead masonry structure provided with two oppositely inclined bores, a hanger comprising a horizontal plate in face-to-face relation with said overhead structure and provided with oppositely inclined holes concentric with said bores, downwardly depending inclined sleeves on said plate concentric with and encircling said holes, pins extending through said sleeves and holes and frictionally engaged in said bores, a vertical threaded bolt depending from said plate between said pins, a disc freely displaceable on said bolt and having an inclined periphery for engaging against and between the said pins, a nut on said bolt locking said disc against said pins, and means between and laterally engaging said pins to urge the same apart.

9. In combination with an overhead masonry structure provided with two oppositely inclined bores arranged at an angle to the horizontal, an anchor hanger comprising a horizontal plate in face-to-face relation with said overhead structure and provided with oppositely inclined holes concentric with said bores, downwardly depending inclined sleeves on said plate concentric with and encircling said holes, pins extending through said sleeves and holes and frictionally engaged in said bores, said pins including flat free extremities inclined at said angle to the horizontal, a vertical threaded bolt detachably depending from said plate midway between said pins, a disc freely displaceable on said bolt and having an inclined periphery for engaging against and between the

inclined extremities of said pins, a nut on said bolt locking said disc against said extremities, a second disc on said bolt and laterally engaging said pins, and a second nut on said bolt engaging said second disc to drive the same in a direction to spread said pins.
